UNITED STATES PATENT OFFICE.

WILLARD STRAUB, OF LOS ANGELES, CALIFORNIA.

THERMOSTAT FOR GAS-FIRED WATER HEATERS.

Application filed May 2, 1922. Serial No. 557,959.

To all whom it may concern:

Be it known that I, WILLARD STRAUB, a citizen of the United States, and a resident of Los Angeles, in the county of Los Angeles and State of California, have invented new and useful Improvements in Thermostats for Gas-Fired Water Heaters, of which the following is a specification.

This invention relates to thermostats for gas fired water heaters, and pertains more particularly to those types of thermostats in which a compound lever acted upon by a thermostatic element, is employed to raise a valve from its seat to allow gas to flow through the valve to a burner.

The invention has for its principal object to provide a thermostatic valve structure in which friction is reduced to a practical minimum.

It will be understood in the consideration of the invention that when a lever acts on a rigid vertical valve stem, the free end of said lever invariably moves through an arcuate path. If the valve stem is properly guided it will of course move in a straight line. The changing path, of that portion of the lever which acts on the valve stem, results in appreciable side thrust and friction between the valve stem and its guide and between said end of the lever and the end of the valve stem. It is therefore another object of my invention to provide a thermostat valve structure in which the valve stem is accurately guided while friction between the stem and its guide, and between the stem and lever is reduced to a practical minimum.

A further object of my invention is to provide a valve which will not readily accumulate dirt and foreign matter, and in which a sharp edge valve seat may be employed without resulting in rapid wear.

Still other objects and advantages will appear hereinafter.

I have illustrated my invention by the accompanying drawings in which,

Figure 1, is a view in vertical section of a preferred embodiment of my invention.

Figure 2, is an enlarged view in vertical section of a part of the embodiment illustrated in Fig. 1, which part is hereinafter known as the valve.

Figure 3, is a view in bottom elevation of the said valve.

More specifically, reference being had to the accompanying drawings and the numerals indicating respective parts thereon,

5 indicates a thermostat casing which is provided with a horizontal wall 6, dividing the interior space of said casing into an upper chamber 7, and a lower chamber 8. An upper wall 9, of the casing is provided with an internally threaded gas inlet opening 10, into which is screw threaded a gas pipe 11. The lower wall 12, of the casing is similarly provided with a gas outlet opening 13, into which is screw threaded a gas outlet pipe 14, leading to a burner (not shown).

Wall 6 is provided with an internally threaded opening 15, into which is screw threaded a valve seat member 16, and upon 70 said valve seat member a valve disc 16', normally rests. It will be apparent that when the valve disc is raised from its seat communication is established between the upper chamber and the lower chamber, and 75 when this communication is established gas may flow from pipe 11, through the chambers 7 and 8, respectively, to the gas outlet pipe 14.

In the lower chamber 8 there is provided 80 a primary lever 17, and a secondary lever 18. These levers are hereinafter jointly known as a compound lever which is in common use in thermostatic devices of the above mentioned type.

An opening 19 is provided in a side wall 20, of the casing, and into this opening is screw threaded a copper tube 21. Said tube is closed at the outer end 22. Said tube being fixed relative to said casing, end 22 will 90 move toward said casing whenever the tube is cooled and contracts. A porcelain rod 23 is disposed within said tube, one end of the rod abutting end 22 of the tube. The other end 25 of the rod abuts a slidable 95 member 26, which rides on the bottom wall 27 of the casing.

Levers 17 and 18 are each mounted to oscillate on a block 29 by knife edge bearings 30 and 31, respectively. Lever 18 is horizontally disposed and is formed with a vertically disposed abutment surface 32. Lever 17 is substantially vertically disposed and has a free upper end 33, which abuts the said abutment surface. In the lower forward portion of lever 17, a concavity 34 is provided, into which a pointed extension 35 of the sliding member 26 extends.

It will be apparent now that the weight of the free end 36 of lever 18, together with 110 any weight to which it may be subjected, will act to hold lever 17 in abutment with

the sliding member 26, and likewise said sliding member will be held in abutment with the porcelain rod.

Such arrangement of parts, including the levers and the valve, is well known and need not be further described herein. The salient feature of my invention resides in the valve disc and valve seat member, each of which I will now describe more in detail.

10 The valve seat member is of cup-like form and is provided with a sharp upstanding annular edge 36'. A plurality of ports 37 are provided in the valve seat element through which gas may flow when the valve 15 disc is held above the annular edge 36'. A central opening 38 is likewise provided for a purpose apparent hereinafter.

The outside diameter of the valve disc is less than the inside diameter of the annular wall 39 of the valve seat member, so that gas may flow freely through the annular space 40 thereby provided.

The valve disc is of appreciable weight and carries a vertically depending rigid 20 valve stem 41, which passes through the central opening 38 in the valve seat member and is a sliding fit therein so as to be accurately guided. Said valve stem carries at its lower end, a ball 42, which is freely 25 mounted therein to rotate universally. Said valve stem may be of any suitable construction, and the ball may be held therein by various means, but in the form of the invention illustrated, said valve stem is 30 formed with a bore 48, and the lower end of the stem is peened slightly as at 49, to retain the ball. A plug 50 is pressed into said bore to limit the upward movement of the ball. It will be seen now that 35 40 I have provided a practically frictionless end to said valve stem.

The valve disc is preferably faced at the lower side by a washer 51; said washer being of any suitably pliable material, but 45 leather is found to be most satisfactory for this purpose. Said washer is held in place by a flange 52, screw threaded into the valve disc.

Lever 18 acts directly upon the ball end 50 of the valve stem, and it will be apparent that friction in all moving parts of the thermostat is reduced to a practical minimum.

The operation of the embodiment illustrated will be apparent from the following:—When the thermostat tube is heated and expanded it will allow the valve to remain on its seat. The position of the parts when the valve is on its seat is shown in 55 Fig. 1. Should the tube be lowered in temperature it will contract and force the sliding member forward toward lever 17. As a result the free end of lever 18, which connects with the ball end of the valve 60 stem, will be forced upwardly through its

characteristic arcuate path. The valve disc will be raised from its seat to allow gas to flow from the upper chamber to the lower chamber. It will be apparent, however, that when the free end of said lever raises the 70 valve disc, side thrust and friction will be minimized because of the ball universally mounted in the lower end of the valve stem.

While I have shown and described a specific embodiment of my invention I do not 75 limit myself to any specific construction or arrangement of parts, except within the appended claims.

I claim:

1. In a thermostatic valve, a thermostat, 80 a valve disc movable to open and closed positions and including a depending rigid valve stem, a ball mounted to revolve freely in the lower end of said stem, a substantially horizontally disposed lever having a free 85 end disposed to contact with said ball, a valve seat element upon which the valve disc normally rests, and a compound lever operatively disposed between said thermostat and said lever; said valve seat element 90 formed with a bore through which said valve stem passes and is guided thereby to move vertically.

2. In a thermostatic valve structure, a chambered casing, a horizontal wall dividing the chamber of the casing into an upper chamber and a lower chamber, a perforated valve seat element carried by said wall, a valve disc disposed in the upper chamber resting on said seat element and normally 100 coacting with the valve seat to close communication between said chambers, a rigid valve stem depending from said valve disc and passing through said valve seat element into the lower chamber in a manner 105 to be guided thereby so that the valve disc may move vertically only, a ball mounted to revolve freely on the lower end of said stem, a compound lever in the lower chamber including a lever having a free end coacting 110 with said ball, and a thermostat carried by the casing and extending into the lower chamber to operatively contact with said compound lever.

3. In a thermostatic valve structure, a 115 chambered casing, a horizontal wall dividing the interior of said casing into an upper chamber and a lower chamber, a valve seat element carried by said upper chamber, a valve disc resting on said seat to close communication between said chambers, a rigid depending valve stem carried by said valve disc and extending downward into the lower chamber; the valve seat element being 120 formed with a bore through which said stem passes so that other than vertical movement of the valve is precluded, a ball mounted to revolve freely in the lower end of said stem, a compound lever in said lower chamber having an end moving through 125 130

an arcuate path and connecting with said ball, and a thermostat extending into the lower chamber and capable upon contraction of raising the free end of said lever 5 to raise the said valve disc from the valve seat element.

4. A thermostatic valve structure, including a thermostat, a lever acted upon by said thermostat so that a free end of said lever

ascends through an arcuate path when the 10 thermostat contracts, a valve, a rigid valve stem depending from said valve, and a ball mounted to revolve freely in the lower end of said stem and disposed to be abutted by said free end of the lever, and means for 15 guiding said valve stem to insure vertical movement, only, of said valve.

WILLARD STRAUB.
